EXPANSIBLE HOSE REEL

James A. Craig, Peekskill, N. Y.

Application August 15, 1933, Serial No. 685,199

9 Claims. (Cl. 299—77)

The present invention relates to an improvement in hose reels and has for its primary object the provision of means whereby, upon occasion of a fire, the hose may be rapidly unreeled, and the water be discharged from the nozzle thereof, before the hose has been fully unreeled, thus saving valuable time.

The main advantage in the present construction is obtained, in that, as soon as the reel is put into operation, the wound up flat hose thereon is immediately and gradually distended with water under pressure, and this hydraulic action causes the reel to expand its capacity in two directions, both laterally and circumferentially, thereby permitting the water to fill the hose at a fast rate and thus the water reaches the flames as quickly as the nozzle can be brought to the fire.

While I have, for the sake of clearness and in order to disclose my invention so that the same can be readily understood, described in general terms and illustrated specific devices and arrangements, I desire to have it understood that this invention is not limited to the specific form disclosed but may be embodied in other ways that will suggest themselves, in view of this broad disclosure, to persons skilled in the art. It is believed that this invention is broadly new and it is desired to claim it as such so that all such changes as come within the scope of the appended claims are to be considered as part of this invention.

In the drawings,

Fig. 1 is a side view, in elevation of the reel with the empty hose shown reeled flat thereon, in normal non-operative position;

Fig. 2 is a sectional view taken on line 2—2, Fig. 1, looking in the direction of the arrows, but with the difference that the hose is shown partly distended with water at its inner portions and the reel thereby caused to be expanded through hydraulic displacement action;

Fig. 3 is a fragmented, sectional view of the reel, only, taken on line 2—2, Fig. 1, looking in the direction of the arrows;

Fig. 4 is a transverse sectional view of the sliding reel seat rung and wheel spoke or arm, taken on the line 4—4, Fig. 3, looking in the direction of the arrows; and

Figs. 5 and 6 are diametral sections similar to Fig. 3 of a modified form of reel, shown normally non-operative in Fig. 5, and expanded in Fig. 6.

The reel comprises two duplicate wheel like structures having circumferential rims 2 which are joined to offset hubs 3 by spokes 1.

The both wheel structures are mounted loosely, as indicated by clearances 25, for sidewise sliding

upon a shaft 5, which is a pipe for carrying water to the reeled hose 14. The pipe shaft 5 is capped with a reel stop cap 6 on its outer end, and at its opposite inner end, external to the coacting wheel, is connected to a rotatable flanged coupling of standard design, so that when the reel is caused to rotate by the withdrawal of the hose therefrom the pipe shaft 5 rotates in the coupling 7.

Coupling 7, in turn is connected firmly to a means for conducting water from a source of water supply, under pressure, such as an elbow connection 8, a pipe 9 connected thereto and having a water controlling valve 10 to cut off or turn on the water, manually, from a source of water, not shown, which enters the stand pipe 9 in the direction of the arrow 11, Fig. 2.

The pipe shaft 5, has attached thereto, near the center of its length, Fig. 2, an extension pipe 12, which as will be noted in Fig. 1, has an inturned end, capped by a hose coupling, generally denoted by 13, whereby the hose 14, at its inner end may be connected to extension pipe 12 to form a continuous water duct from stand pipe 9 to the hose nozzle 15, Fig. 2.

The inturned hubs 3—3 of the wheels have cut outs 4—4 therein to provide a passage clearance for the extension pipe 12, when the two wheels or reel sides are in normal non-expanded condition, as in Fig. 3.

The arms 1 of the wheels forming the reel sides are channeled as at 17, Figs. 3 to 6, both to gain longitudinal strength and to form guideways for the sliding hose rungs 16, one of which is transversely mounted between each opposed pair of arms 2, shown dotted in Fig. 1 and in full lines in Fig. 4.

The hose rungs 16 are provided with reduced machined ends 18, Fig. 4, in order to provide wider surfaces with which to support the hose and to gain in ease of sliding in the channels 17, during the operative periods of the reel.

The hose rungs 16 are loosely mounted in the channels 17, are full floating, and are each supported in their operative assembled positions between the reel sides by a curved fulcrum spring 19, Fig. 4 to which the rungs are riveted by a rivet 24. The opposed ends of the fulcrum springs 19 are curled and are joined to the sides of the webs of the spoke arms 1 which form the channel 17, by riveted-in bearing pins 23.

Between the rungs 16 and the hubs 3—3 each of the spokes 1 are further joined by a coiled wire extension spring 21, the ends of which are affixed to the opposed spokes 1—1 by pins 22—22 fixed in the webs of the channel 17.

As thus described, and shown in Fig. 4, the reel is in non-operative position, and when the hose is wound thereon, and the device set for use, as in Fig. 1, the hose is in flat empty form 5 and reeled rather closely on the rungs and to the reel sides. With the valve 10 closed, the apparatus is ready to function.

When a fire occurs, the operator opens valve 10, grasps the nozzle 15 and runs towards the flames. Immediately upon the opening of the valve 10 the water flows into the flat hose 14 at its center through extension pipe 12, and distends the hose. As this distension requires more space than the normally flat wound hose requires, 10 the distended hose forces the floating hose rungs inwardly towards the hubs 3-3 and this action, through the toggle like action of the fulcrum springs 19, causes the reel sides to move apart, with a sliding action on pipe shaft 5, until stopped by the members 6 and 7, and, thus, increased 15 reel space for the rapidly distending hose is obtained by a duplex action, i. e. the inward contraction of the hose rung ring and the outward movement of the reel sides from position A to dotted position B, Fig. 4.

The inward contraction of the hose rungs is fully illustrated in Fig. 2, in which the central sections of the hose are shown in the partially distended position and have moved the floating rungs 16 towards the pipe shaft 5, with a consequent flattening of fulcrum spring 19, an extension of spring 21, and an expansion movement 20 of the reel sides.

As above described, by the time the operator and the nozzle have reached the fire zone, water 25 is flowing from the nozzle at full pressure, because the flow of water into the hose is more rapid than the nozzle can be carried to the fire zone.

After the reel has been emptied of the hose and the reel sides and rungs are relieved of the burden of the hose, the fulcrum springs 19, supplemented by the extension springs 21, bring the reel sides back to their normal contracted positions A.

45 Figs. 5 and 6 disclose a modified form of fulcrum rung, as a substitute for the resilient fulcrum spring 19 and rung 16, of Fig. 3. In these views, like parts, having like functions, of Figs. 1 and 4 inclusive have similar indices as in Figs. 1 to 4. In Fig. 5 there is shown a pair of toggle links 25 pivoted together at 27, with their outer ends pivoted to the side walls of the channel 17 of the spokes 1. In this figure the reel sides are shown in normal, non-operative, contracted hose holding position A.

In Fig. 6, the reel sides are shown in operative, expanded position B, giving a consequent side expansion of the reel sides and an inward radial increase of space, due to the inward movement 60 of the toggle rungs 25. The toggle rungs 25 of these two figures are prevented from going to dead center, as in Fig. 6, by the stop action of the cap plug 6 and the rotatable coupling 7. As described for Figs. 1 to 4, when the structure of 65 Figs. 5 and 6 are released of hose load the springs 21 on each arm 1, contract the reel sides, and the toggle rungs 25 are automatically reset to the position shown in Fig. 5.

What I claim is:

70 1. A hose reel comprising spaced reel sides between which a hose may be wound; and means for supplying water under pressure to said hose; one of said sides being movable from the other by the distending action of the hose when water under pressure is admitted to the hose.

2. A rotatably mounted hose reel comprising spaced reel sides yieldably relatively outwardly movable from each other; a collapsible hose adapted to be wound about said reel between said sides, the sides being sufficiently spaced to allow several overlapping collapsed convolutions of the hose side-by-side and superposed in the reel; means for supplying water under pressure to the inner end of the hose before and while unwinding, thereby to distend the inner convolutions of the 10 hose and separate said sides, thereby to relieve pressure on the inner and outer convolutions to facilitate the passage of water to and through all of the convolutions.

3. A hose reel comprising spaced reel sides; 15 and rungs disposed between the sides about which a hose may be wound; means for supplying water under pressure to the wound hose; said rungs being movable inwardly and one of said sides being movable from the other by the distending 20 action of the hose when water under pressure is admitted to the hose.

4. A rotatably mounted hose reel comprising spaced reel sides yieldably relatively outwardly movable from each other; rungs disposed between the sides and inwardly yieldably movable toward the axis of the reel; a collapsible hose adapted to be wound about said rungs, the sides being sufficiently spaced, and the rungs sufficiently remote from the periphery of the sides to allow 25 several overlapping collapsed convolutions of the hose side-by-side and superposed in the reel; means for supplying water under pressure to the inner end of the hose before and while unwinding thereby to distend the inner convolutions of 30 the hose, separate said sides and move the rungs inwardly, thereby to relieve pressure on the inner and outer convolutions to facilitate the passage of water to and through all of the convolutions.

5. A hose reel comprising a valve controlled 40 source of water supply under pressure; a rotatable coupling pipe shaft communicating with said source; an extension pipe for connecting a hose to said coupling pipe shaft; a pair of reel sides mounted on said coupling pipe shaft for movement toward and from each other and rotation with said coupling shaft; springs for drawing said sides toward each other; toggle rungs connecting said reel sides and mounted to move outwardly from the shaft at their mid part when the reel 50 sides move toward each other; and stop means on the coupling pipe for limiting the inward movement of the toggle rungs.

6. In combination a hose reel comprising a 55 valve controlled source of water supply under pressure including a rotatable coupling pipe shaft communicating with said source, and a collapsed hose wound upon said reel; an extension pipe for connecting the hose to said coupling pipe shaft; a pair of reel sides mounted on said coupling pipe shaft for movement toward and from each other and rotation with the shaft; a plurality of springs for drawing said sides toward each other; of spaced toggle rungs connecting said reel sides and mounted to move outwardly 60 from the shaft at their mid part when the reel sides move toward each other and movable toward and from the coupling pipe shaft, and about which said hose may be wound while said toggle rungs are at their radial outward limit of movement; the admission of water to said hose causing the hose to press said toggle rungs radially inwardly and separate said reel sides, thereby facilitating the rapid filling of the hose.

7. An expandible hose reel comprising in com- 75

- 5 combination a pair of spaced wheels, rungs, for receiving a hose, spanning the space between said wheels, said rungs moving bodily inwardly radially of said wheels upon the admission of water to a hose coiled about said rungs, and members bridging the space between said wheels in the path of movement of said rungs, movement of said rungs elongating the said bridging members to increase the hose carrying capacity of the reel.
- 10 8. An expandible hose reel comprising in combination a pair of spaced wheels, rungs, for receiving a hose, spanning the space between said wheels, each of said rungs constituting a toggle

with the two ends thereof attached to said wheels, inward movement of said toggle rungs due to the admission of water to a hose coiled about said rungs forcing the said wheels apart to increase the hose carrying capacity of the reel.

9. A hose reel comprising spaced reel sides between which a hose may be wound; a collapsed hose wound upon said reel, means for supplying water under pressure to said hose; and means operated by the distending action of the hose 10 when water under pressure is admitted to the hose for separating said sides.

JAMES A. CRAIG.
